UNITED STATES PATENT OFFICE.

JAMES V. DUNBAR, OF NEW ORLEANS, LOUISIANA.

ART OF CANNING SHRIMP.

Application filed August 3, 1922. Serial No. 579,503.

This invention relates to the art of canning shrimp and particularly to the packaging of shrimp in metal containers. One of the objects of the invention is the prevention of discoloration of the packaged product.

Another object of the invention is to provide a container that will effectively protect the shrimp from discoloration irrespective of the position in which the container is placed when stored.

Still another object of the invention is the construction of a paper or other non-metallic flexible receptacle for enclosing the shrimp, used in combination with a metallic container and arranged to interpose a plurality of thicknesses between the shrimp and container both at the top and bottom.

With the above and other objects in view, my invention consists in the improved art of canning shrimp illustrated in the accompanying drawings, described in the following specification, and particularly claimed, and in such variations and modifications thereof as will be obvious to those skilled in the art to which my invention relates.

In the drawings accompanying and forming a part of this specification, and wherein the preferred embodiment of my invention is illustrated:

Figure 1 is a perspective view of a can having the front broken away to show a receptacle embodying the principle of my invention.

Figure 2 is a side sectional view of the can shown in Figure 1.

Figure 3 is a perspective view of the paper receptacle with the upper end unfolded.

Figure 4 is an underneath view of the receptacle shown in Figure 3.

Referring now in detail to the several figures, the numeral 1 represents a cylindrical can having a flat top 2 and bottom 3.

This can or container is formed in the well-known manner and need not here be described.

In packing shrimp it has been found necessary to coat the inside of the can including the top and bottom with a thin layer of lacquer to prevent chemical reaction between the metal of the can at the point of contact with the shrimp, which causes discoloration of the latter and impairment of its quality. This coating is shown in the drawing at 4 in Figures 1 and 2. It has

been found by experience that the lacquer coating cannot be relied upon entirely to give the desired protection particularly at the seams of the can or through rupture of the lacquer due to indenting of the can or through imperfect application of the lacquer.

It has heretofore been attempted to further ensure the protection of the shrimp from discoloration by surrounding them with an enclosure of paper or other non-metallic fabric to keep them out of physical contact with the lacquered surface of the can, or to rely upon the paper enclosure altogether, dispensing with the coating of lacquer. Various means of carrying out this system of protection have been tried out such as lining the can with a cylinder of paper with separate paper disks covering the top and bottom, or enclosing the shrimp in a muslin bag or by placing them in a paper bag, folding it at the top and inserting it within the metallic container. With all of these expedients a considerable proportion of failures in the perfect keeping of the product is expectable due to misadventures occurring during the processing of the shrimp or in the storing of the finished product. Where separate disks of paper are used in the top and bottom of the can they are apt to be misplaced or folded over during the filling of the can or its subsequent processing, resulting in the shrimp being left in contact with the metallic surface. I have found that even when a one-piece paper receptacle is used such as a bag, folded over at the top, discoloration of the shrimp is likely to occur when the can is stored with the folded end of the receptacle uppermost. This is due to the fact that the shrimp lies by gravity against the bottom of the receptacle the concentrated juices therefrom being pressed by the weight of the shrimp through the bottom membrane of said receptacle and having a corrosive effect upon the metallic surface of the bottom of the container.

My invention proceeds to the elimination of discoloration of the shrimp by providing a one-piece paper receptacle which is folded at both ends, interposing a plurality of thicknesses of paper between the ends of the receptacle and the metallic container so as to hold the shrimp away from close proximity to the surfaces thereof irrespective of which end of the container is lowermost.

when the latter is stored. To this end I have provided the paper receptacle 5 which is made from a single flat sheet folded to form a seam 6 and having the upper and 5 lower ends folded together to form a complete one-piece enclosure. The end folds are made by first folding inwardly the front face 8 of the receptacle including the seam 6. The left hand side is then folded in as 10 shown at 9 and then the right hand side as shown at 10 and finally the rear portion 11. When the bottom of the receptacle has been thus folded it is placed within the container, the appropriate quantity of shrimp placed 15 therein, and the upper end folded together in a similar manner. It will be observed from the figures that by folding the ends of the paper receptacle, a number of thicknesses of paper intervene between the shrimp 20 and the metallic ends of the container whether the can is set open with the bottom down as shown in Figure 1, or inverted. It is not essential that the plurality of thicknesses of paper should be uniform in number or extend over the entire top and 25 bottom end surfaces of the container. It is sufficient that the points and angles of the end folds of the receptacle overlap so that some portion of the ends of receptacle are of a plurality of thicknesses, for the thicker portions will hold the thinner portions away 30 from the metal ends of the container sufficiently to accomplish the designs of the invention.

25 While paper is here referred to for preferred use in the construction of the recep-

tacle it is clearly within the scope of the invention to make use of any substance which lends itself to the carrying out of the functions herein set forth. Nor is the invention 40 limited to any particular method of folding the ends of the paper, it being quite sufficient that the paper be so folded as to provide some portion of both the top and bottom ends of the receptacle with a thickness 45 of a plurality of layers of the material from which the receptacle is constructed. And while the invention in the embodiment shown in the drawings and described in the specification is applied to a can having a 50 lacquered coating it is by no means limited to such application but may be used in combination with any type of metallic container whatsoever.

Having described my invention what I 55 claim as new and desire to secure by Letters Patent, is:—

In a package for the preservation of shrimp a container having a metallic bottom and top, a one-piece paper receptacle 60 within said container for enclosing the shrimp, both ends of said receptacle being folded to form sectors of more or less incidental irregularity which overlap substantially from the sides of said receptacle to 65 the center thereof, thereby imposing a plurality of thicknesses of paper between the bottom and top of said container and the contents of said receptacle.

In testimony whereof I have hereunto set 70 my hand.

JAMES V. DUNBAR.
